WRINGER

Walter L. Kauffman, II, Erie, Pa., assignor to
Lovell Manufacturing Company, Erie, Pa., a
corporation of Pennsylvania

Application March 17, 1937, Serial No. 131,328

15 Claims. (Cl. 68—263)

Power wringers are commonly provided with release devices and are also provided with some means for resetting pressure after release has been effected. Ordinarily the resetting device retains the pressure of the rolls after the resetting, the release device also retaining pressure and operating either directly on the resetting device or independently thereof. In the present invention the resetting device is relieved of pressure after the pressure is set, the release device taking on the pressure. The invention also involves the arrangement of the resetting and release device at the same end of the wringer, also an improved release device. Features and details of the invention will appear from the specification and claims.

A preferred embodiment of the invention is illustrated in the accompanying drawings as follows:

Fig. 1 shows a front elevation of a wringer partly in section.

Fig. 2 an elevation of an end of the wringer partly in released position.

Fig. 3 a section on the line 3—3 in Fig. 1.

Fig. 4 an elevation partly in section showing a modification of the wringer.

Fig. 5 an elevation partly in section of the modification showing the parts in released position.

Fig. 6 a section on the line 6—6 in Fig. 4.

Fig. 7 shows a latch member as used in the modification of Figs. 4 and 5 having, however, similar features to the latch member of Fig. 1, such common features being similarly designated.

Fig. 8 an enlarged view of an end of the wringer in section showing the release mechanism of both modifications.

1 marks a base of the wringer, 2 and 3 side stiles, 4 a lower roll having a shaft 5, 6 an upper roll having a shaft 7. The shaft 5 is journaled in bearings 8 mounted at the lower end of the stile and actuated by any suitable power device (not shown) forms a driving means for the wringer rolls. The shaft 7 is journaled in bearings 9 slidably mounted in the upper end of the stile. A spring 10 engages the upper bearings and forms the pressure means, the adjustment of the spring being accomplished by a screw 11 operating through a fitting 11a on the top bar 12. The top bar 12 is detachably locked with the stile 3 by the interlocking shoulders 13 and 14 on the stile and end of the top bar respectively.

A latch member 15 has the two sides extending downwardly into the stile 2. A pin 16 extends through the top bar and side plates pivotally

connecting the latch member with the top bar. The plates are connected by the cross piece 17 across the top of the latch member. Each of the side plates has a slot 18 with an offset 19. A locking means 20 which is preferably in the form of pins extending through the walls of the stile extend through the slots. When the means 20 is in the offset portion 19 it is adapted to lock the top bar with the stile. The latch member is releasably held in this set position by trip member 21. The trip member 21 is pivotally mounted in the top bar by a pin 22. A lip 23 of the trip member extends over the cross plate 17 and locks the latch member in set position. When the lip 23 is lifted by the depression of the outer end of the trip member this releases the latch member and the pressure of the spring 10 cams the latch member out of the offset portion 19 of the slot, and the slot 18 permits the upward or free movement of the latch member in the stile, thus permitting the end of the top bar to swing up to release pressure on the rolls. This upward movement of the release end of the top bar disengages the interlocking shoulders 13 and 14 so that the entire top bar is released thus providing further freedom for the rolls.

The resetting mechanism comprises a toggle lever, a link 24 of the lever being channel formed straddling the top bar and the side stiles. It is pivotally connected by a pin 25 with the end of the top bar. The other link 26 of the toggle lever is pivotally connected by a pin 27 with the upper end of the stile. This link has a slot 28 with an offset 29, the offset being an elbow forming a projection 30 on the link 26. A pin 31 passes through the side walls of the link 24 and through the slot 28. As the toggle approaches the bottom or closed position, the link 26 is stopped so that with the final movement of the link 24 the pin 31 is carried out of the offset 29 and into register with the slot 28. A spring 30a yieldingly holds the link 26 so as to retain the pin 31 in the offset during the setting operation as indicated in Fig. 2. As the link 24 approaches its set position the spring passes off the projection 30 and thus permits the stopping of the link 26 and permits the parts to retain their position close to the stile through gravity alone.

In the operation of the device, starting with the parts in set position, a release is accomplished by depressing the trip member 21 and releasing the latch member 15, immediately the latch member through the camming action on the offset 19 swings to bring the pin 20 in register with the slot 18 and this permits of the upward movement

of the latch member and top bar. At the same time the pin 31 is free to move upwardly in the slot 28 so that the release movement can be consummated. The resetting is accomplished by lifting the link 24 up to a position which brings the pin 31 opposite the offset 29. When it reaches this position both gravity and the spring 30 move the link laterally relatively to the pin 31 so as to lock the link 26 with the link 24 at their point of connection. The link 24 can then be swung downwardly effecting a resetting pressure on the spring. As the link reaches its lower position the latch member 15 reaches a position bringing the pin 20 opposite the offset 19 and the camming action of the upper wall of the offset swings the link sidewise carrying the pin 20 into the offset and the upper end of the plate 17 out from under the lip 23, thus permitting the trip member to move downwardly into set position. Preferably a spring 21a is arranged between the latch member 15 and the trip member 21, this spring yieldingly tending to reset the trip member and the latch member.

In the modification shown in Figs. 4, 5 and 6, the wringer and the release mechanism are similar to the wringer and release mechanism shown in Figs. 1, 2, 3 and in Figs. 7 and 8, except the sides of the bearing blocks extend below the shaft 7. The latch member 15a is not connected at the bottom as is the latch member 15 in Fig. 1, and the top of the wringer in Figs. 4, 5 and 8 is notched at 2a to give clearance for the pivot pins 20. The resetting mechanism comprises a toggle lever operating between the frame and the top bar. A link 32 of the toggle lever is pivotally connected at 33 with the top bar. A link 34 is in the form of a wire bail, the ends of the bail being pivotally connected at 35 with the link 32. A cross member 34a of the bail extends through a strap 36 which is secured to the face of the side stile 2 providing a slot 36a between the face of the stile and the strap. The upper end of the strap forms a shoulder 37 which is adapted to limit the upward movement of the cross member 34a of the bail. To reset the wringer, the bail is lifted and as the link 34 reaches the shoulder 37 the link 32 acting as a lever forces the end of the top bar down, resetting the pressure on the spring. As soon as the release device engages, the link 32 is dropped, the slot 36a permitting the downward movement of the link 34.

It will be noted that by transferring this load from the toggle to a separate member, the release may be effected through this separate member and thus make it possible to accomplish a release without violent action of the toggle members.

What I claim as new is:

1. In a wringer having a frame; rolls mounted in the frame; and pressure means for exerting pressure on the rolls; the combination with the frame and pressure means of a lever actuated pressure resetting device for resetting the pressure means comprising a toggle, the links of which have operative connections with each other and the frame and pressure means, at least one of said connections being releasable and released at the completion of the resetting operation; and a release device for releasing the pressure means, said device having means taking over the pressure of the pressure means from the resetting device.

2. In a wringer having a frame comprising a base and side stiles; rolls mounted in the frame;

a releasable top bar; and a pressure means exerting pressure from the top bar on the rolls; the combination with a stile, pressure means and top bar of a resetting device comprising a toggle, the links of said toggle having operative connections between each other and between the top bar and a stile, at least one of said connections being releasable and released at the completion of the resetting operation; and a release device for the top bar having means taking over the pressure from the toggle upon completion of the resetting movement.

3. In a wringer having a frame comprising a base and side stiles; rolls mounted in the frame; a releasable top bar; and pressure means exerting pressure on the rolls from the top bar; the combination with the frame and top bar of a release device for the top bar comprising a latch member connected with the top bar and having a slot with an offset portion, a securing member on the frame extending into the slot, the securing member when in the offset locking the latch member with the frame, and a trip device holding the latch member in position to retain the securing member in the offset of the slot, said trip device releasing the latch member to permit the securing member to pass out of the offset for a release operation, said trip device being mounted on the top bar.

4. In a power wringer having a frame; rolls mounted in the frame; a pressure means for exerting pressure on the rolls; a pressure re-setting device for the pressure means whereby during resetting movement of the resetting device pressure is applied to the rolls; and a driving means for the rolls; the combination with the driving means, pressure means and resetting device of a safety release device for the pressure means, said release device comprising means taking over the pressure of the pressure device from the re-setting device, said re-setting device operating independently of the driving means.

5. In a power wringer having a frame; rolls mounted in the frame; a pressure means for exerting pressure on the rolls; a pressure re-setting device for the pressure means whereby during resetting movement of the resetting device pressure is applied to the rolls; and a driving means for the rolls; the combination with the driving means, pressure means and resetting device of a safety release device for the pressure means, said release device comprising means taking over the pressure of the pressure device from the re-setting device, said release device and re-setting device operating independently of the driving means.

6. In a power wringer having a frame; rolls mounted in the frame; a pressure means for exerting pressure on the rolls; a pressure resetting device for resetting the pressure means whereby during resetting movement of the resetting device pressure is applied to the rolls; and a driving means for one of the rolls; the combination with the pressure and driving means of a safety release device for releasing the pressure means, said device being operative independently of the driving means and comprising means taking over the pressure of the pressure means from the resetting device.

7. In a power wringer having a frame; rolls mounted in the frame; a pressure means for exerting pressure on the rolls; a pressure resetting device for resetting the pressure means whereby during resetting movement of the resetting device pressure is applied to the rolls; and driv-

ing means for one of the rolls; the combination with the pressure and driving means of a safety release device for releasing the pressure means, said device being operative independently of the driving means and comprising means automatically taking over the pressure of the pressure means from the resetting device.

8. In a power wringer having a frame; rolls mounted in the frame; a pressure means for exerting pressure on the rolls; a lever actuated resetting device for resetting the pressure means whereby during resetting movement of the resetting device pressure is applied to the rolls; and a driving means for one of the rolls; the combination with the pressure and driving means of a safety device for releasing the pressure means, said device being operative independently of the driving means and comprising means taking over the pressure of the pressure means from the resetting device.

9. In a power wringer having a frame comprising a base and side stiles; rolls mounted in the frame; a driving means for the rolls; a pressure means for exerting pressure on the rolls; and a releasable top bar; the combination with the pressure means, driving means, frame and top bar of a pressure resetting device for resetting the pressure means whereby during resetting movement of the resetting device pressure is applied to the rolls operatively connected with the top bar and the frame; and a safety release device for the top bar having means taking over the pressure between the top bar and a stile at the completion of the setting movement of the setting device, said release device being operative independently of the driving means.

10. In a wringer having a frame, rolls mounted in the frame, and pressure means for exerting pressure on the rolls; the combination with the frame and pressure means of a lever actuated resetting device for the pressure means comprising a toggle, one of the links of the toggle having a slot having a portion lengthwise of the link and an offset portion; connections between the links and between the toggle and the pressure means and the frame, one of the connections having a member projecting into the slot and engaging the offset portion formed in the slot for locking the connection during a resetting operation, the member being free to move in the lengthwise portion of the slot at the completion of the resetting operation.

11. In a power wringer having a frame comprising a base and side stiles, rolls mounted in the frame, pressure means for exerting pressure on the rolls, a driving means for the rolls and a top bar; the combination with the top bar and a stile of a pressure resetting device having links pivotally connected to each other and to the top bar and a stile, at least one of the connections being releasable and released at the completion of the resetting movement; and a release device for the top bar at the same end of the top bar as the resetting device, said release device effecting a release independently of the resetting device and the driving means.

12. In a wringer having a frame comprising a base and side stiles, rolls mounted in the frame, a top bar releasably mounted on the side stiles, and pressure means exerting pressure on the rolls from the top bar; the combination with the

frame and top bar of a toggle resetting device between the top bar and the frame comprising a link pivotally connected to the top bar, and a link having a pin and slot connection with a side stile, the slot extending along the side stile and limiting the upward movement of the link in the connection, the link connected to the top bar having an extension, the extension and link forming a lever, operating to depress the top bar with an upward movement of the extension and with the link connected to the slot engaging the upward end of the slot, said slot permitting free movement of the connected link downwardly therein during a return movement of the lever and permitting a direct upward movement of the lever through the movement of the pin in the slot upon a release of pressure.

13. In a wringer having a frame, rolls mounted in the frame and pressure means for exerting pressure on the rolls, the combination with the frame and pressure means; of means for releasing the pressure means, a lever actuated pressure resetting device for resetting the pressure means comprising a slot and pin connection, the slot having a shoulder preventing functional movement of the pin in the slot during the resetting movement and permitting the pin to disengage itself from the shoulder and move in the slot at the completion of the resetting operation, the pin and slot connection permitting freedom of motion in the connection during a release movement of the pressure means.

14. In a wringer having a frame comprising a base and side stiles, rolls mounted in the frame, a top bar, and a pressure means exerting pressure from the top bar on the rolls, the combination with a stile, pressure means and top bar of a resetting device comprising a toggle, the links of said toggle being pivotally connected together at one end of each link and the opposite end of one link pivotally connected to the top bar, and the opposite end of the other link pivotally connected to a side stile, said toggle converting a lateral movement of the connecting pivot between the links to a relative vertical movement of the opposite ends of the links forcing, through such relative vertical movement, a downward movement of the top bar for resetting pressure on the pressure means, at least one of said pivotal connections being releasable and released at the completion of the resetting operation.

15. In a wringer having a frame, rolls mounted in the frame, and pressure means for exerting pressure on the rolls, the combination with the frame and pressure means of a resetting device comprising a toggle, the links of the toggle at all times being pivoted to each other and the frame and pressure means, and one link of the toggle being extended forming with the link an actuating lever to actuate the toggle to draw the frame and pressure means pivots toward each other to reset the pressure means, one pivot of the toggle device having a lost motion connection whereby a resetting swinging movement of the lever will reset the pressure on the pressure means through the swinging movements of the toggle links and permit, through said lost motion connection, a non-swinging release movement of the toggle.

WALTER L. KAUFFMAN, II.
